SOUND RECORD

Dénes von Mihály, Berlin-Wilmersdorf, Germany,
assignor to the firm Julius Pintsch Aktien-
gesellschaft, Berlin, Germany

Application March 28, 1929, Serial No. 350,692
In Germany December 8, 1928

7 Claims. (Cl. 274—41.6)

Various sound records upon film sensitive to light are already known, as well as apparatus for the production of such films and apparatus for the reproduction of the records. The oldest 5 of these devices consists in influencing the light of an arc lamp inductively by microphone currents and allowing the varying light of the arc lamp to act through a slit upon a sensitive film moving rapidly past it. To the sound vibrations 10 there correspond varying bright and dark strips upon the film. If such a film is passed in front of a constant source of light, and the rays of the source of light darkened to a varying extent by the variations in the depth of the blackening 15 of the film are thrown upon a cell which is sensitive to light and which is connected in a joint circuit with a telephone, corresponding variations in the resistance of the sensitive cell are produced and corresponding variations of current in 20 the telephone, so that the sound originally recorded can again be heard.

The advantages of such a reception and reproduction of sound, as compared with those of a disc talking machine are immediately obvious. 25 Since both the recording and the reproduction are effected by means of a ray of light no wear of the sound record carrier can occur. Furthermore duplication is cheap and simple. The record carrier is unbreakable.

30 The invention consists essentially in that the record carrier is constituted by an endless strip of film on which the record of the sound runs along lines which are parallel to the edges of the film, which lines intermittently pass from one 35 into the other at one point of the film. This arrangement has the advantage as compared with the known arrangement in which the sound record runs along a spiral line, that when the film breaks the same can be stuck together without 40 difficulty whilst this is not possible with the known arrangement, since in that case the ends of the sound record will no longer correspond to one another.

It is also known to provide films with a plurality of record strips being parallel to one another and to the edges of the film. However, such records are not continuous and for reproducing the film has to be moved alternately in opposite directions which involves a complicated 45 driving mechanism and causes interruptions of the sound reproduction at the end of each strip.

The accompanying drawing illustrates by way of example a sound record according to the present invention.

55 Figure 1 is a perspective view of an endless band

of film provided with a sound record according to the invention.

Fig. 2 is an enlarged detail in plan of a part of the film shown in Fig. 1.

Referring to the drawing in detail, the endless 5 band of light sensitive film designated at 1 is guided by rollers 2 and is provided with a continuous photographic sound record 3 of less width than the film. The sound record extends a number of times around the film along lines which 10 are parallel to each other and to the edges of the film, the record shifting at intervals and passing completely around the film between two such displacements.

These lines form a plurality of sound track 15 sections which are disposed generally longitudinally of the film and the shifting of the record forms crossover or bridging sections 4 connecting the end of one sound track section with the beginning of another sound track section. 20

What I claim is:—

1. A sound record for talking machines and the like, consisting of an endless band of light sensitive film on which sound has been photographically recorded in lines extending a number of 25 times around the endless band parallel to the edges of the film, the record shifting from one line to the next at intervals and passing completely round the endless band between two such displacements. 30

2. An endless transparent light-sensitive standard type motion picture film having a photographic sound record thereon, said record being of a width less than that of said film, said record comprising a plurality of portions paralleling and 35 adjacent each other and paralleling the edges of the film, said portions being joined to form a single record.

3. An endless transparent light-sensitive standard type motion picture film having a photographic sound record thereon, said record being of a width less than that of said film, said record comprising a plurality of portions paralleling and adjacent each other and paralleling the edges of the film, said portions including bridging sections between the successive parallel portions, the 40 whole forming a single record. 45

4. A uni-directional endless transparent light-sensitive standard type motion picture film having a photographic sound record thereon, said 50 record being of a width less than that of said film, said record comprising a plurality of portions paralleling and adjacent each other and paralleling the edges of the film, said portions including diagonal bridging sections between the 55

successive parallel portions, the whole forming a single record.

5. An endless transparent light-sensitive standard type motion picture film having a photographic sound record thereon, said record being of a width less than that of said film, said record comprising a plurality of portions paralleling and adjacent each other and paralleling the edges of the film, said portions including rectilinear 10 bridging sections between the successive parallel portions, the whole forming a single record.

6. In a transparent light-sensitive endless film a single narrow photographic sound record thereon and disposed in parallel sections, said

sound record including integral crossover sections between the said several parallel sections.

7. A transparent light-sensitive endless film, including a unitary photographic sound record comprising a plurality of sound tracks disposed generally longitudinally of the film and substantially coextensive therewith, and continuous bridging sections disposed between the several longitudinal sound-track sections and extending in the general direction of the said several sound-track sections for connecting the end of one sound track section with the beginning of another sound track section. 10

DÉNES VON MIHÁLY.
